UNITED STATES PATENT OFFICE

159,981

HAIRBRUSH

Lewis H. Gustafson, Northampton, and Lewis J. Halberstadt, Williamsburg, Mass., assignors to Pro-Phy-Lac-Tic Brush Company, Florence, Mass., a corporation of Delaware

Application October 12, 1949, Serial No. 5,442

Term of patent 14 years

(Cl. D86—10)

To all whom it may concern:

Be it known that we, Lewis H. Gustafson, a citizen of the United States, residing at Northampton, Commonwealth of Massachusetts, and Lewis J. Halberstadt, a citizen of the United States, residing at Williamsburg, Commonwealth of Massachusetts, have invented a new, original, and ornamental Design for a Hairbrush, of which the following is a specification, reference being had to the accompanying drawing, forming a part hereof.

Referring to the drawing:

Fig. 1 is a top perspective view of a hairbrush, showing my new design;

Fig. 2 is a side elevational view; and

Fig. 3 is a bottom plan view.

We claim:

The ornamental design for a hairbrush, as shown.

LEWIS H. GUSTAFSON.

LEWIS J. HALBERSTADT.
